UNITED STATES PATENT OFFICE.

THOMAS H. CHUBB, OF POST MILLS, VERMONT.

REEL-FASTENER FOR FISHING-RODS.

SPECIFICATION forming part of Letters Patent No. 235,511, dated December 14, 1880.

Application filed May 10, 1880. (No model.)

To all whom it may concern:

Be it known that I, THOMAS H. CHUBB, residing in Post Mills, county of Orange, State of Vermont, have invented certain Improvements in Reel-Fasteners for Fishing-Rods, of which the following is a specification.

This invention relates to the manner of securing the reel of a fishing-rod to the butt of the latter, whereby the surface of such butt is left intact, my present improvement being intended more especially for rod-butts composed of different varieties of cane, in which the removal of the outer enamel is objectionable for several reasons. I also avoid the labor and expense of cutting a recess for reception of the reel-plate.

The drawings accompanying this specification represent, in Figure 1, a side elevation, and Fig. 2 a longitudinal section, of a portion 20 of a fishing-rod containing my improvements, the heel-plate being added to Fig. 2, while Fig. 3 is a like view of the old method of securing the reel.

Heretofore, in order to secure the reel plate 25 or band to the rod-butt by rings, it has been the universal practice to cut a recess in the surface of the butt to receive the reel-plate and prevent the reel from turning or shifting its position upon the butt, a fixed ring being 30 secured to the butt at the lower end of the recess, under which one end of the reel-plate is inserted, while a loose ring is employed to slip over the opposite end of the said reel-plate, thereby confining the reel to the rod, while, 35 lastly, a narrow stop-ring is employed to prevent escape of the loose ring last named.

In Fig. 3 of the drawings the butt of the rod is shown at A, the recess at a, the fixed ring at b, the loose ring at c, and the stop-ring 40 at d.

In addition to the labor and expense of producing the recess a, it mars the surface of the butt in any material, but especially in the case of butts made of cane the removal of the enamel disfigures and weakens the butt, and is 45 objectionable in other respects.

In Fig. 1 of the drawings above named, A represents the lower portion of the butt or first joint of a fishing-rod; and in carrying my 50 present improvement into practice I dispense with the recess a before alluded to, and to pre-

vent turning or shifting of the reel upon the rod I employ a short tube or sleeve, B, to encompass the butt, and I strike up in or add to the upper end of such sleeve a swell or enclosure, C, which is adapted to receive the lower end of the reel-plate and confine it closely to the surface of the butt. 55

Above the sleeve B, I employ a loose ring, D, and a stop-ring, E; but the ring D is necessarily larger in diameter than if the reel-plate were let in flush with the surface of the butt, and the outer periphery of the stop-ring must project a greater distance from the surface of the butt to correspond to the increased 65 diameter of the clasp-ring D.

To provide a stop-ring which may be manufactured at small cost and possess the requisite lightness, I strike up from thin metal, as shown in Fig. 2 of the drawings, in lieu of a 70 brazed ring, as heretofore.

In addition to the advantages before named as accruing from my improvement, I am enabled to change the position of the reel upon the butt, should it be desirable to do, to overcome the bend or set of the butt, for the reason that by the use of the sleeve B, with its socket, the butt is not disfigured or scarred, and it is only necessary to extract the pin which secures the sleeve to the butt, and turn 75 the sleeve upon the butt to any desired extent. Of course, in such an event the rings of the butt must be changed to correspond to the change of the sleeve. 80

Heretofore the swell or socket C has been 85 formed of an independent piece and soldered or brazed to the tube. I reduce the cost and greatly enhance the appearance.

I claim—

In a fishing-rod butt, the following elements 90 in combination: the unbroken or undisturbed surface of the butt, as a seat to the reel-plate, the fixed sleeve with its swell or socket, the enlarged loose-fitting clasp-ring, and the enlarged struck-up stop-ring. 95

In testimony whereof I have hereunto affixed my signature in the presence of two witnesses.

THO. H. CHUBB.
